CLAIM

I claim the ornamental design for dual perfume bottles and tray, as shown and described.

DESCRIPTION

FIG. 1 is a perspective view of dual perfume bottles and tray showing my new design;

FIG. 2 is a front elevational view thereof;

FIG. 3 is a right side elevational view thereof;

FIG. 4 is a top plan view thereof;

FIG. 5 is an exploded perspective thereof; and,

FIG. 6 is a top plan view of the tray member.
